UNITED STATES PATENT OFFICE

107,161

DESIGN FOR A BEANPOT

Chester C. Soule, Portland, Maine

Application October 13, 1937, Serial No. 72,147

Term of patent 14 years

To all whom it may concern:

Be it known that Chester C. Soule, a citizen of the United States, residing at Portland, in the county of Cumberland and State of Maine, has invented a new, original, and ornamental Design for a Beanpot, of which the following is a specification, reference being had to the accompanying drawing, forming part thereof, wherein:

I claim:—

The ornamental design for a beanpot, as shown.

CHESTER C. SOULE.
